DESIGN FOR A HANDBAG

Henry Green, Far Rockaway, N. Y.

Application February 6, 1941, Serial No. 98,798

Term of patent 3½ years

To all whom it may concern:

Be it known that I, Henry Green, a subject of Poland and a resident of the United States of America, in the city of Far Rockaway, county of Queens, and State of New York, have invented a new, original, and ornamental Design for a Handbag, of which the following is a specification, reference being had to the accompanying drawings, forming part thereof, wherein,

Figure 1 is a front elevational view of a handbag showing my new design in an open position.

Figure 2 is an end elevational view of Figure 1, with a portion of the handle omitted for convenience of illustration.

Figure 3 is a front elevational view of the handbag in a closed position, and

Figure 4 is an end elevational view thereof.

The rear of the handbag is substantially the same in appearance as the front.

The characteristic features of my design reside in the handbag disclosed having in the open ends thereof self-adjusting opposed side mirrors and gussets of the specific configuration shown.

I claim:

The ornamental design for a handbag, substantially as shown and described.

HENRY GREEN.
